CLAIM

The ornamental design for a upper portion of a face shield, as shown and described.

DESCRIPTION

FIG. 1 is a front side perspective view of an upper portion of a face shield according to the present design;

FIG. 1A is an enlarged perspective view of the portion shown in the square area identified as FIG. 1A in FIG. 1; FIG. 2 is a top perspective view of the face shield upper portion of FIG. 1;

FIG. 2A is an enlarged perspective view of the portion shown with the square area identified as FIG. 2A in FIG. 2; FIG. 3 is a front elevational view of the face shield upper portion of FIG. 1; and,

FIG. 3A is an enlarged front view of the portion shown with the square area identified as FIG. 3A in FIG. 3.

The broken lines represent portions that form no part of the claimed design.
